UNITED STATES PATENT OFFICE.

SAMUEL MOZART HAUSER, OF ELMHURST, NEW YORK.

CURTAIN ROD.

Application filed November 5, 1921. Serial No. 513,028.

To all whom it may concern:

Be it known that I, SAMUEL M. HAUSER, a citizen of the United States, and resident of Elmhurst, in the county of Queens and 5 State of New York, have invented a new and Improved Curtain Rod, of which the following is a full, clear, and exact description.

My invention relates to a curtain rod, and aims to provide certain new and useful im- 10 provements in connection with a device of this character.

In connection with curtain rods, it is a well appreciated fact that considerable difficulty has been experienced for the rea- 15 sons that the usual curtain rod has been relatively cumbersome and expensive in manufacture, and also for the reason that the connections existing between the plates and rod proper have been such that they 20 will readily become jammed, and also in certain types of rods, the connection has not been of sufficient strength to withstand the strain imparted thereto incident to the supporting of relatively heavy hangings.

Still further objections have been noted 25 in connection with devices of this character, and with this in mind, my present invention aims to provide a curtain rod which shall primarily be capable of being readily and 30 economically manufactured, and which rod, when finished will present an extremely pleasing appearance and be light in weight, so as to be capable of being readily manipulated with respect to its supporting plates.

Still further objects of this invention are 35 the provision of a device of the character stated in which a connection will be established between the supporting plates and the body of the rod in such a manner that 40 the same may be quickly applied, and be detached from the plates, it being noted that this connection will also be of such a nature as to at all times insure a positive support, prevent sagging, and also preclude any 45 possibility of a longitudinal distortion of the ends of the rod.

Other objects of this invention will be- 50 come apparent in the annexed specification taken in connection with the drawings which latter present one practical embodiment of the same, and in which—

Figure 1 is a perspective view of a rod embodying my improved construction and showing the same in fixed position upon the 55 window sash;

Figure 2 is a perspective view of one of the ends of the rod and the co-operating plate detached from each other;

Figure 3 is a similar view but showing 60 these elements in engaging position;

Figure 4 is a transverse sectional view taken along the line 4—4 and in the direc- 65 tion of the arrows illustrated in Figure 1.

In the drawing, the numerals 5 designate 70 a pair of similarly constructed telescoped sections or rods having their longitudinal edge portions formed with interfitting flanges 6 connected as illustrated in Figure 4.

The end portions of the rods 5 are pro- 75 vided with extensions 7 having inwardly di- rected branches 8 adapted for connection with base plates 9.

Each base plate has its end portions 80 formed with apertured ends for the recep- tion of suitable fastening devices by means of which the plate may be secured to a frame 1. The base plates 9 are provided with upper and lower lugs 11 and 12 re- 85 spectively, the upper lugs being provided with slots 14 adapted for the reception of the inwardly directed lug or branch 8 of the adjacent rod. Figures 2 and 3 illustrate that the lower lugs 12 are grooved longitudinally to receive the lower extension 7 whereby the rods 5 are securely though detachably connected to the base.

It will be observed that the upper and lower lugs 11 and 12 are struck out from 90 the base plates 9 between the openings 10 and these attaching plates may be formed from a single blank of metal.

I claim—

A curtain rod comprising a base plate 95 provided at its end portions with attaching means and provided between said attaching means with upper and lower struck out lugs, the upper lug being provided with a slot and the lower lug being provided with a longitudinal depression forming a groove, and a rod having upper and lower exten- 100 sions provided with terminal branches ex- tending inwardly toward each other, the in- wardly extending terminal branches of the upper extension being extended through the slot in the upper lug and the lower extension 105 of said rod being received in said groove whereby the rod is detachably connected to said base plate.

SAMUEL MOZART HAUSER.
